STEAM BOILER

Charles E. Lucke, New York, N. Y., assignor to
The Babcock & Wilcox Company, Newark,
N. J., a corporation of New Jersey

Application October 3, 1935, Serial No. 43,321

11 Claims. (Cl. 122—336)

This invention relates in general to the construction of steam generating units, and more particularly to steam generating units in which a water cooled furnace is located wholly at one side of the main tube bank of a two-drum steam boiler. Steam generating units of this type are mainly characterized by their relatively low cost of manufacture and maintenance, small floor space and headroom requirements, and relatively wide range of capacity operation at high efficiencies.

A main object of my invention is the provision of a steam generating unit of the character described with an improved location of the fuel burning means in one of the furnace walls extending longitudinally of the main tube bank with the fuel discharged having a length of travel in the furnace through a path directed so as to cause substantially the entire furnace volume to be filled with fuel burning in suspension at various stages of combustion and the initial portion of the path to receive a substantial amount of heat radiation from the higher temperature section of the path, thus insuring complete combustion of the fuel in suspension in the furnace at a high rate of heat release. Another main object of my invention is the provision in a steam generating unit of the character described of a baffle system for the tube bank which will cause a heating gas flow relative to the tubes of the tube bank such as to effect a high rate of heat transfer throughout the tube bank, a low draft loss in the unit, and a rapid rate of fluid circulation through the tubes, whereby a relatively high steaming capacity and generating efficiency can be easily maintained in operation.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described preferred embodiments of my invention.

Of the drawings:

Fig. 1 is a somewhat diagrammatic sectional elevation of one form of my invention taken on the line 1—1 of Fig. 2;

Fig. 2 is a horizontal section taken on the line 2—2 of Fig. 1;

Fig. 3 is a horizontal section taken on the line 3—3 of Fig. 1;

Fig. 4 is a view similar to Fig. 1 of a modification;

Fig. 5 is a horizontal section taken on the line 5—5 of Fig. 4; and

Figs. 6 and 7 are views similar to Fig. 1 of two other modifications.

In the embodiments of my invention illustrated in the drawings, the boiler settings are substantially rectangular in horizontal and vertical cross-section, being formed by vertical side walls 10 and 12, end walls 11 and 13, a top wall or roof 14, and a bottom wall or floor 15, hereinafter specifically described. In the unit shown in Fig. 2, the horizontal distance between the side walls 10 and 12 is substantially greater than between 15 the end walls 11 and 13, but this ratio will vary with the size of the unit.

The pressure parts of the steam boilers shown in Figs. 1—5 and 7 include a horizontally elongated upper steam and water drum 16 and a lower water drum 17 in axial alignment therewith, both of which extend the full distance between the side walls 11 and 13 and adjacent to but spaced from the side wall 12. The drums 16 and 17 are connected by a vertically disposed bank of substantially straight water tubes 18 extending between and having their ends radially connected to the drum walls at both sides of the vertical plane including the longitudinal axes of the drums. As shown in Figs. 1 and 2, the innermost longitudinal tube row 18' is spaced from the adjacent tube row a substantially greater distance than that between the remaining longitudinal rows of the tube bank.

A row of water tubes 19 extends laterally from the lower drum 17 to a longitudinal header 20 at the bottom of the side wall 10, the spaces between the tubes being closed by refractory material 21 constructed to form a floor 15. A row of tubes 22 extends upwardly from the header 20 to a similarly arranged top header 23. The spaces between the tubes 22 are filled with refractory material to form the inner portion of the side wall 10. A corresponding row of roof tubes 24 connects the header 23 to the upper drum 16, with the spaces between the tubes closed by refractory material to form the underside of the top wall 14. The end walls 11 and 13 are each provided at their inner sides with a row of cooling tubes 25 extending between upper and lower transverse headers 26 and 27 respectively, having their inner ends connected to the drums 16 and 17 respectively by nipples 28. The walls 10, 11, 13, 14, and 15 and tube bank collectively define the limits of the boiler furnace 30, wholly

cated at one side of the tube bank 18 and between the vertical limits of the drums 16 and 17. The construction of the walls 10, 11, 13 and 14 with a substantial amount of exposed tube surface permits the ratio of cold surface to total wall surface and to furnace volume to be varied over a relatively wide range to secure the most effective mean furnace temperature for different operating conditions and for different sizes of furnaces.

The boiler furnace shown in Figs. 1-3 is adapted for the burning of various fluid fuels, such as pulverized fuel, oil, or gas, in suspension, and is particularly suitable for the burning of pulverized coal. The provisions for this purpose preferably consist of one or more flat flame burners 31, such as the multiple outlet pulverized fuel burner shown in a pending application of Ervin G. Bailey, Serial No. 484,739, filed Sept. 27, 1930, mounted in corresponding burner ports 32 formed in the roof 14 intermediate the ends of the furnace and adjacent the drum 16. The nozzle outlets of each fuel burner are positioned within an air box 33 opening to the corresponding burner port and the fuel streams pass between corresponding roof tubes 24, to produce a longitudinally elongated stream of mixed pulverized coal and air. Each fuel burner is downwardly directed with its axes of discharge intersecting the side wall 10 adjacent its lower end, whereby the fuel stream tends to follow a flame path initially directed toward the side wall 10, but curving downwardly above the floor 15 towards the tube bank 18, whereby substantially all of the furnace volume will be effectively utilized by the elongated flame path so provided to permit substantially complete combustion of the fuel stream before reaching the tube bank. The fuel stream thus passes through the furnace in a direction transversely of the tube bank, i. e., the fuel burner is located in a furnace wall extending longitudinally of the tube bank with its axis of discharge in a vertical plane transverse to that wall.

The specific construction of the furnace bottom 15 will mainly depend upon the mean furnace temperature desired to be maintained and the ash fusion temperature of the pulverized fuel to be used. The furnace shown in Figs. 1 and 2 is designed for dry ash removal. For this reason the furnace bottom is constructed to provide a relatively flat horizontal floor for receiving the ash separating from the burning fuel. The deposited ash may be periodically removed from the floor by pushing or blowing the same into an ash pit 35, constructed in the floor adjacent the end wall 11, as shown in Fig. 2. Clean-out openings 36 are provided in the walls 11 and 13 at the floor level and in the ash pit to facilitate removal of the deposited ash.

The fuel burner arrangement described is especially adapted for an advantageous heating gas flow relative to the tube bank 18. As shown in Fig. 1, the tube bank 18 is provided with a baffle system consisting of a tube baffle 40 extending downwardly from the upper drum 16 and formed by providing the upper half of the tubes 18' with studs 41, and filling the corresponding inter-tube spaces with refractory material 42, as shown in Fig. 3. The lower end of the baffle 40 has a downwardly inclined lateral extension 43 terminating adjacent the outer side of the tube bank. The lower ends of the tubes 18' are also provided with refractory embedded studs to form a short tube baffle 44 which protects that side of the lower drum from furnace radiation and forms a pocket

for holding material, such as deposited furnace dust, to protect the upper surface of the drum from the high temperature gases. At the opposite side of the drum 17 is a dust hopper 45, which receives dust swept off the drum by the gases or separated out of the heating gases above the hopper.

The side wall 12 is as shown, spaced throughout its extent from the outer side of the tube bank 18. A baffle 46 extends horizontally from the wall 12 across most of the tube bank 18 at a level intermediate the baffle extension 43 and the upper drum 16, whereby the baffles 40, 43, and 46 in conjunction with the side walls 11, 12, and 13 define three serially connected superposed gas passes 50, 51, and 52 extending transversely of the tube bank 18, with the passes 50 and 51 progressively tapering and connected by a gas turning and equalizing space 53 between the tube bank 18 and wall 12, and the passes 51 and 52 connected by a gas turning and equalizing space 54 between the tube baffle 40 and the main portion of the tube bank. At the side of the upper drum 16 opposite the furnace and in communication with the outer end of the gas pass 52 is arranged a heating gas outlet 55 controlled by one or more dampers 56. The heating gases from the furnace will thus flow transversely of the tubes 18 throughout their height through gas passes having flow areas proportioned for a low draft loss, and highly effective heat transfer by reason of the mass flow conditions. The passage of the hottest gases first across the lower portions of the tubes effects a rapid fluid circulation in the tubes 18, because the average fluid density in the tubes due to the presence of steam in the water will be reduced over a greater vertical height of tube compared with the water in downcomer tubes.

The steam generated in the boiler passes out of the upper drum 16 through outlet connections 60 leading to a looped tube self-draining superheater formed by a pair of longitudinally extending horizontal headers 61 and 62 located adjacent the drum 17 and connected by nested rows of looped tubes 63 positioned in the gas pass 50 in the space between the tubes 18' and the adjacent row of tubes 18. The superheater tubes are arranged in position to receive a portion of their heat by radiation from the furnace chamber through the spaces between the tubes 18'. The nested superheater tube rows are preferably spaced to provide a uniform transverse spacing of the tube legs and the tubes are bent at their lower ends to pass between the tubes 18'.

In operation, the streams of pulverized fuel and air are discharged downwardly over a substantial portion of the furnace length in a path initially directed towards the side wall 10 and then curving towards the lower portion of the tube bank. Combustion of the fuel is substantially completed before the stream reaches the tube bank, and the ash separated in suspension drops to the furnace floor normally in a dry condition. The portions of the tubes 18' in front of the superheater further cool any ash particles in suspension and also protect the superheater tubes from an excessive amount of radiant heat. The gases then pass over the superheater tubes and the remaining portion of the tube bank and turn upwardly through the space 53 into the gas pass 51. The space 53 effectively maintains a uniform distribution of the heating gases and permits ash particles separating from the heating gases to drop directly into the ash hopper 45. The gases then pass inwardly through the second pass 51 to the

space 54 which functions in the same manner as the space 53. Any ash deposited on the baffle extension 43 can be blown into the ash hopper. The gases then pass outwardly through the top 5 gas pass 53 to the heating gas outlet 55.

The modification illustrated in Figs. 4 and 5 is primarily distinguished from the form shown in Figs. 1 to 3 by the different provisions for treating the incombustible ash residue of the 10 fuel. In Fig. 4 the furnace bottom is shown as designed for the collection of the ash in a molten condition, the tubes 19 being covered by a layer of slag resistant material 65 shaped to support a pool of molten slag which can be continuously 15 or intermittently tapped through a slag tap opening 66 located in the side wall 11. In view of the molten condition of the ash particles in suspension the tubes 18' and the next adjacent row of tubes 18 of the tube bank have their 20 lower portions bent to form a slag screen at the furnace side of the superheater. As shown in Figs. 4 and 5, the portions of the tubes 18' below the vertical portion of the baffle 40 are alternately bent inwardly to varying extents to form 25 spaced rows of tubes 18^a and 18^b. Alternate tubes in the laterally adjacent row of tubes 18, which is also spaced from the remaining rows, have their lower portions bent inwardly in front 30 of the superheater to form a third row of screen tubes 18^c. The bent portions of this row of tubes aid in supporting and cooling angularly arranged tile pieces 43' forming the inner portion of the baffle extension 43.

In Fig. 6 I have illustrated another modification in which the tube bank 18 is constructed and arranged similarly to that of Fig. 4, but in Fig. 6 the walls 11, 13, 14, and 15 are extended to increase the width of the furnace. The floor tubes 19 are also bent at their outer ends to provide an elevated portion of the furnace floor in which is formed a burner port 32' for a substantially upwardly directed fuel burner 34'. As diagrammatically indicated in Fig. 6, the fuel 40 stream initially passes through a vertical flame 45 path along the outer side of the furnace and then downwardly toward the lower portion of the tube bank. The lower portion of the furnace floor receives substantially all of the ash separating in the furnace and the furnace and 50 floor may be designed for the reception and removal of the ash therefrom in dry form as shown in Figs. 1 and 2 or in a molten condition as shown in Fig. 4.

In Fig. 7 I have illustrated another form of my invention in which the drums 16 and 17 are laterally offset and the tube bank 18 correspondingly inclined, leaving the furnace 30' substantially trapezoidal in vertical cross-section as distinguished from the rectangular formation in 55 Figs. 1, 4, and 6. In this form, the upper header 23 is eliminated and the portion of the top wall 14 above the furnace is relatively short. The fuel burner 34^a is arranged to discharge vertically downward through a burner port 32^a in the top wall. This furnace construction is especially suitable for the collection of slag deposits in a molten condition on the bottom and their removal through a slag tap opening 66^a. The baffle system for the tube bank is arranged substantially as shown in Figs. 1, 4, and 6 to provide a similar flow of heating gases relative to the tube bank. The baffle extension 43^a is arranged horizontally instead of inclined, while the superposed baffle 46^a is downwardly inclined 70 across the tube bank and provided with a hori-

zontal extension 46^b between the tube bank and side wall 12, the baffle system thus defining three superposed serially connected gas passes 50', 51', and 52'. The setting space made available above the baffle extension 46^b and below the top 5 wall 14 at the outer side of the gas pass 52 is advantageously utilized for an auxiliary fluid heater 70, such as an economizer or air heater. The steam boiler construction illustrated in Fig. 7, like those shown in Figs. 1-6, provides a relatively long flame path in the fluid cooled furnace in a direction transversely of the tube bank and effects a passage of the heating gases transversely of the tubes in the tube bank for substantially their entire length. All of the 10 described forms of my invention are adapted for manufacturing in a range of sizes having substantially the same overall efficiency.

While in accordance with the provisions of the statutes I have illustrated and described herein 20 the best forms of my invention now known to me, those skilled in the art will understand that changes may be made in the form of the apparatus disclosed without departing from the spirit of the invention covered by my claims, and that 25 certain features of my invention may sometimes be used to advantage without a corresponding use of other features.

I claim:

1. A two-drum steam boiler comprising substantially parallel upper and lower horizontal drums, a bank of vertically disposed water tubes connecting said drums, side, top and bottom walls defining a furnace wholly at one side of and open along its length to said tube bank and closed at its lower end, a heating gas outlet at the opposite side of said tube bank, cooling tubes extending from said lower drum to the outer side wall of said furnace and along said outer side wall and top wall to said upper drum, fuel 40 burner means mounted in one of said furnace walls in position to discharge a stream of fuel in a direction transversely of said tube bank and to cause the gases of combustion to approach said tube bank substantially throughout the 45 length thereof, a baffle system for said tube bank arranged to form a plurality of serially connected superposed gas passes providing a generally vertical flow of gases relative to said tube bank and a substantially transverse flow of gases 50 over the tubes of said tube bank throughout their lengths, and a group of looped superheater tubes arranged within and substantially parallel to the tubes of said tube bank across the first gas pass traversed by the combustion gases. 55

2. A two-drum steam boiler comprising substantially parallel upper and lower horizontal drums, a bank of vertically disposed water tubes connecting said drums and arranged at both sides of the plane including the longitudinal axes of 60 said drums, side, top and bottom walls defining a furnace wholly at one side of and open along its length to said tube bank and closed at its lower end, a heating gas outlet along the opposite side of said tube bank, cooling tubes extending 65 from said lower drum to the outer side wall of said furnace and along said outer side wall and top wall to said upper drum, fuel burner means mounted in one of said furnace walls at a point intermediate the length of said drums and arranged to discharge a stream of fuel in a direction 70 transversely of said tube bank and to cause the gases of combustion to approach said tube bank substantially throughout the length thereof and adjacent one of said drums, a baffle system 75

- for said tube bank arranged to form a plurality of serially connected superposed gas passes providing a generally vertical flow of gases relative to said tube bank and a substantially transverse flow of gases over the tubes of said tube bank throughout their lengths, and a group of looped superheater tubes arranged within and substantially parallel to the tubes of said tube bank across the first gas pass traversed by the combustion gases.
3. A two-drum steam boiler comprising substantially parallel upper and lower horizontal drums with their axes in vertical alignment, a bank of vertically disposed water tubes connecting said drums and arranged at both sides of the plane including the longitudinal axes of said drums, side, top and bottom walls defining a furnace wholly at one side of and open along its length to said tube bank and closed at its lower end, a heating gas outlet along the opposite side of said tube bank adjacent said upper drum, cooling tubes extending from said lower drum to the outer side wall of said furnace and along said outer side wall and top wall to said upper drum, fuel burner means mounted in one of said furnace walls at a point intermediate the length of said drums and arranged to discharge a stream of fuel in a direction transversely of said tube bank and to cause the gases of combustion to approach said tube bank substantially throughout the length thereof and adjacent one of said drums, a baffle system for said tube bank arranged to form three serially connected superposed gas passes providing a generally vertical flow of gases relative to said tube bank and a substantially transverse flow of gases over the tubes of said tube bank throughout their lengths, said baffle system including means forming a vertical baffle extending from one of said drums to a level intermediate the height of said tube bank, a rearward extension on said baffle separating the first and second gas passes, and a horizontally arranged baffle extending inwardly from the outer side of said tube bank intermediate the height of said vertical baffle and separating the second and third gas passes, and a group of looped superheater tubes arranged substantially parallel to the tubes of said tube bank across the first gas pass.
- 50 4. A two-drum steam boiler comprising substantially parallel upper and lower horizontal drums, a bank of vertically disposed water tubes connecting said drums, side, top and bottom walls defining a furnace wholly at one side of said tube bank and closed at its lower end adjoining said lower drum by a fluid cooled floor, a heating gas outlet at the opposite side of said tube bank, cooling tubes extending from said lower drum to the outer side wall of said furnace and along said outer side wall and top wall to said upper drum, fuel burner means mounted in one of said furnace walls and arranged to discharge a stream of fuel in a direction transversely of said tube bank causing the gases of combustion to approach the lower portion of said tube bank substantially throughout the length thereof and adjacent said lower drum, and a baffle system for said tube bank arranged to form a plurality of superposed serially connected gas passes, the lowermost of which opens directly to said furnace throughout the length thereof above said lower drum, whereby a generally upward flow of gases relative to said tube bank and a substantially transverse flow of gases over the tubes of said tube bank throughout their lengths will be effected.
- 55 5. A two-drum steam boiler comprising substantially parallel upper and lower horizontal drums, a bank of vertically disposed water tubes connecting said drums, side, top and bottom walls defining a furnace wholly at one side of said tube bank and closed at its lower end, a heating gas outlet along the opposite side of said tube bank, cooling tubes extending from said lower drum to the outer side wall of said furnace and along said outer side wall and top wall to said upper drum, fuel burner means mounted in said bottom wall and arranged to upwardly discharge a stream of fuel between said cooling tubes in a direction transversely of said tube bank and causing the gases of combustion to approach said tube bank throughout the length thereof, and a baffle system for said tube bank arranged to form a plurality of superposed serially connected gas passes, the lowermost of which opens to said furnace throughout the length thereof, whereby a generally upward flow of gases relative to said tube bank and a substantially transverse flow of gases over the tubes of said tube bank throughout their lengths will be effected.
- 60 6. A two-drum steam boiler comprising substantially parallel upper and lower horizontal drums, a bank of vertically disposed water tubes connecting said drums and arranged at both sides of the plane including the longitudinal axes of said drums, side, top and bottom walls defining a furnace wholly at one side of said tube bank and closed at its lower end, a heating gas outlet along the opposite side of said tube bank and adjacent said upper drum, cooling tubes extending from said lower drum to the outer side wall of said furnace and along said outer side wall and top wall to said upper drum, fuel burner means mounted in one of said furnace walls and arranged to discharge a stream of fuel in a direction transversely of said tube bank and to cause the gases of combustion to approach said tube bank substantially throughout the length thereof and adjacent one of said drums, a baffle system for said tube bank arranged to form a plurality of superposed gas passes providing a generally vertical flow of gases relative to said tube bank throughout their lengths will be effected.
- 65 7. A two-drum steam boiler comprising substantially parallel upper and lower horizontal drums, a bank of vertically disposed water tubes connecting said drums and arranged at both sides of the plane including the longitudinal axes of said drums, side, top and bottom walls defining a furnace wholly at one side of said tube bank and closed at its lower end, a heating gas outlet along the opposite side of said tube bank and adjacent said upper drum, cooling tubes extending from said lower drum to the outer side wall of said furnace and along said outer side wall and top wall to said upper drum, fuel burner means mounted in one of said furnace walls and arranged to discharge a stream of fuel in a direction transversely of said tube bank and to cause the gases of combustion to approach said tube bank substantially throughout the length thereof and adjacent one of said drums, a baffle system for said tube bank arranged to form a plurality of superposed gas passes providing a generally vertical flow of gases relative to said tube bank throughout their lengths will be effected.
- 70 8. A two-drum steam boiler comprising substantially parallel upper and lower horizontal drums, a bank of vertically disposed water tubes connecting said drums and arranged at both sides of the plane including the longitudinal axes of said drums, side, top and bottom walls defining a furnace wholly at one side of said tube bank and closed at its lower end, a heating gas outlet along the opposite side of said tube bank, cooling tubes extending from said lower drum to the outer side wall of said furnace and along said outer side wall and top wall to said upper drum, fuel burner means mounted in one of said furnace walls and arranged to discharge a stream of fuel in a direction transversely of said tube bank and to cause the gases of combustion to approach said tube bank substantially throughout the length thereof and adjacent one of said drums, a baffle system for said tube bank arranged to form a plurality of superposed gas passes, the lowermost of which opens directly to said furnace throughout the length thereof above said lower drum, whereby a generally upward flow of gases relative to said tube bank and a substantially transverse flow of gases over the tubes of said tube bank throughout their lengths will be effected.
- 75 9. A two-drum steam boiler comprising substantially parallel upper and lower horizontal drums, a bank of vertically disposed water tubes connecting said drums and arranged at both sides of the plane including the longitudinal axes of said drums, side, top and bottom walls defining a furnace wholly at one side of said tube bank and closed at its lower end, a heating gas outlet along the opposite side of said tube bank, cooling tubes extending from said lower drum to the outer side wall of said furnace and along said outer side wall and top wall to said upper drum, fuel burner means mounted in one of said furnace walls and arranged to discharge a stream of fuel in a direction transversely of said tube bank and to cause the gases of combustion to approach said tube bank substantially throughout the length thereof and adjacent one of said drums, a baffle system for said tube bank arranged to form a plurality of superposed gas passes, the lowermost of which opens directly to said furnace throughout the length thereof above said lower drum, whereby a generally upward flow of gases relative to said tube bank and a substantially transverse flow of gases over the tubes of said tube bank throughout their lengths will be effected.

bank and a substantially transverse flow of gases over the tubes of said tube bank throughout their lengths, and the innermost tubes in said bank having portions bent and spaced to form a slag screen for the tubes in the first pass.

8. A two-drum steam boiler comprising substantially parallel upper and lower horizontal drums, a bank of vertically disposed water tubes connecting said drums and arranged at both sides of the plane including the longitudinal axes of said drums, side, top and bottom walls defining a furnace wholly at one side of said tube bank and closed at its lower end, a heating gas outlet along the opposite side of said tube bank, cooling tubes extending from said lower drum to the outer side wall of said furnace and along said outer side wall and top wall to said upper drum, fuel burner means mounted in said top wall adjacent said upper drum and arranged to discharge a stream of fuel in a direction transversely of said tube bank and to cause the gases of combustion to approach the lower portion of said tube bank substantially throughout the length thereof and adjacent said lower drum, a baffle system for said tube bank arranged to form a plurality of superposed gas passes providing a generally upward flow of gases through said tube bank and a substantially transverse flow of gases over the tubes of said tube bank throughout their lengths, and the innermost tubes in said bank having their lower ends spaced to form a slag screen for the tubes in the first pass.

9. A two-drum steam boiler comprising upper and lower horizontal drums, a bank of vertically disposed water tubes connecting said drums and arranged at both sides of the plane including the longitudinal axes of said drums, side, top and bottom walls defining a furnace wholly at one side of said tube bank and closed at its lower end, a heating gas outlet along the opposite side of said tube bank, fuel burner means mounted in one of said furnace walls and arranged to discharge a stream of fuel in a direction transversely of said tube bank and to cause the gases of combustion to approach said tube bank substantially throughout the length thereof, a baffle system for said tube bank arranged to form three superposed gas passes providing a generally upward flow of gases relative to said tube bank and a substantially transverse flow of gases over the tubes of said tube bank throughout their lengths, said baffle system including a vertical baffle extending downwardly from said upper drum along the inner side of said tube bank, a lateral extension of said baffle separating the first and second passes, and a horizontally arranged baffle extending inwardly across said tube bank and separating the second and third passes, said vertical baffle being widely spaced from the main portion of said tube bank to provide a gas turning and equalizing space connecting the second and third gas passes, the outer side of said tube bank being spaced from the adjacent wall to form a gas turning and equalizing space therebetween connecting the first and second gas passes, and an ash hopper below said last mentioned space.

10. A two-drum steam boiler comprising walls forming a setting of substantially rectangular horizontal cross-section, upper and lower drums adjacent one side of said setting, a bank of ver-

tically disposed water tubes connecting said drums and having transversely spaced inner and outer sections, a group of looped superheater tubes extending vertically within the space between said inner and outer tube bank sections, water tubes extending laterally from said lower drum to the opposite side wall of said setting and upwardly along said side wall and across to said upper drum and defining a fluid cooled furnace chamber at one side of and open along its length to said tube bank inner section, a heating gas outlet at the opposite side of said tube bank, fuel burner means mounted in one of said setting walls at a point intermediate the length of said drums and arranged to discharge a stream of fuel into said furnace chamber in a direction transversely of said tube bank whereby the combustion gases approach said tube bank inner section substantially throughout the length thereof, the tubes in said tube bank inner section being arranged to form a protecting screen between said furnace chamber and said superheater tubes, and a baffle system for said tube bank arranged to form a plurality of serially connected superposed gas passes across said tube bank outer section providing a substantially transverse flow of gases over the tubes of said outer section substantially throughout their lengths.

11. A two-drum steam boiler comprising walls forming a setting of substantially rectangular horizontal cross-section, upper and lower drums at one side of said setting having their longitudinal axes in vertical alignment, a bank of vertically disposed water tubes connecting said drums and divided into a pair of transversely spaced inner and outer sections, a group of looped superheater tubes extending vertically within the space between said tube bank inner and outer sections, water tubes extending laterally from said lower drum to the opposite side wall of said setting and along said side wall and across to said upper drum and defining a fluid cooled furnace chamber wholly at one side of said tube bank and open along its length to said tube bank inner section, a heating gas outlet along the opposite side of said tube bank outer section adjacent said upper drum, fuel burner means arranged to discharge a stream of fuel between said wall water tubes into said furnace at a point intermediate the length of said drums and in a direction transversely of said tube bank and whereby the combustion gases approach said tube bank substantially throughout the length thereof, the tubes in said tube bank inner section being arranged to form a protecting screen between said furnace chamber and said superheater tubes, and a baffle system for said tube bank including an L-shaped baffle extending downwardly from said upper drum and transversely across said tube bank outer section and a horizontally extending baffle extending inwardly partly across said tube bank outer section above the transverse section of said L-shaped baffle to form a plurality of serially connected superposed gas passes across said tube bank outer section providing a generally vertical flow of gases relative to said outer section and a substantially transverse flow of gases over the tubes thereof substantially throughout their lengths.

CHARLES E. LUCKE.
